UNITED STATES PATENT OFFICE.

GEORGE C. HOUCK, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

PAD FOR IRONING AND PRESSING MACHINES.

Application filed February 14, 1923. Serial No. 618,999.

This invention relates to pads for ironing and pressing machines, mangles etc., and has for its object a particularly simple and efficient means for attaching the outer covering 5 of cloth to the under side of the pad, which means does not project beyond the plane of the lower side of the pad, so that the pad can rest on a flat bed without forming depressions in the bed.

10 The invention consists in the novel features and in the combinations and constructions hereinafter set forth and claimed.

In describing this invention, reference is had to the accompanying drawings, in which 15 like characters designate corresponding parts in all the views.

Figure 1 is an elevation of a pad applied to the lower buck or bed of a pressing machine.

20 Figure 2 is an inverted plan view, partly broken away, of the pad.

Figure 3 is an enlarged sectional view on line 3—3, Fig. 2.

This pad comprises a means on the bottom 25 side thereof to which the margin of the cloth covers can be readily attached and detached, such means being arranged approximately in the plane of the bottom side of the pad, so that the pad will rest flatwise 30 and evenly on the face of the bed or buck or other support.

The body of the pad here illustrated comprises a plurality of springs 1, secured to the base 2, and a layer 3 of felt or padding overlying the springs. A covering 4 of cloth 35 overlies the felt padding.

The base 2 is here shown as a sheet metal plate, the springs being secured at their lower ends to the plate by rivets 5. The 40 base rests on the heads 6 of these rivets except where the heads are covered by the margin of the covering cloth 4.

The means by which the covering 4 may be attached, to, and detached from, the base 45 plate, comprises a plurality of prongs 7 arranged around the margin of the plate and with their points directed inwardly toward the center or the median line of the plate, these prongs extending in a direction parallel to the plane of the outer face of the plate and being located in, or near such plane 50 of the outer face of the plate.

In the illustrated embodiment of my invention, the pad is shown as mounted on

the flat horizontal face of the lower buck 55 of a pressing machine and hence the prongs extend in a horizontal plane.

As here illustrated, the prongs 7 extend in a direction crosswise of openings 9 formed in the plate 2, and these openings are the 60 entrances of shallow depressions 10 in the plate, which depressions are formed by punching or distorting the plate inwardly at intervals. The prongs are preferably struck from the metal from which the depressions 65 are formed.

In use, the margin of the covering along one side or half thereof, is folded under the plate 2 and caught on the prongs 7 along one margin of the plate 2. Then the covering is stretched over the body of the pad and the opposite margin of covering caught on the adjacent prongs of the base.

Owing to the openings 9 or depression 10, the covering can readily be hooked over the 75 prongs, and owing to the arrangement of the prongs, the pad lies flatwise on the bed or buck without special provision being made for the prongs such as grooves in the buck to receive the prongs.

The pad may be held on the buck 8 in any suitable manner, and as here shown, it is secured to the buck 8 by elastic members, as coiled springs 11 extending crosswise of the under side of the pad near its ends, these 85 springs 11 being looped around the ends of the buck. The ends of the springs are secured to lugs 12 depending from the margin of the pad and lapping the edge faces of the buck 8.

What I claim is:

A pad for ironing and pressing machines, comprising a base plate, padding mounted on the base plate, having a covering for the padding, the base plate being formed with 95 depressions at its lower face, and prongs extending across the depressions and inwardly toward the center of the plate, the prongs being located substantially in the plane of the base plate, and the covering having its 100 margin folded under the base plate and caught on said prongs.

In testimony whereof, I have hereunto signed my name, at Syracuse, in the county of Onondaga and State of New York, this 105 2nd day of February, 1923.

GEORGE C. HOUCK.
